(57) **CLAIM**

The ornamental design for a waterproof ring, as shown and described.

DESCRIPTION

FIG. 1 is a front perspective view of a waterproof ring, showing my new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is an exploded front perspective view thereof;

FIG. 10 is a section view taken along line 10-10 in FIG. 4; and,

FIG. 11 is a section view taken along line 11-11 in FIG. 4. The evenly spaced broken lines shown in the drawings depict portions of the waterproof ring that form no part of the claimed design.

1 Claim, 10 Drawing Sheets
